UNITED STATES PATENT OFFICE.

OSCAR U. ZERK, OF NEWARK, NEW JERSEY, ASSIGNOR TO BASSICK ALEMITE CORPORATION, OF CHICAGO, ILLINOIS, A CORPORATION OF DELAWARE.

LUBRICANT COMPRESSOR.

Application filed January 24, 1925. Serial No. 4,514.

My invention relates to improvements in lubricant compressors, and is particularly concerned with the provision of a novel type of compressor adapted to form a part of 5 a lubricating system that comprises a plurality of fittings and a compressor for successively making sealed contact with these fittings and forcing lubricant, under high pressure, into them.

10 The objects of my invention are:

First, to provide a compressor comprising a barrel or low pressure cylinder for holding a substantial quantity of lubricant, a high pressure cylinder of comparatively small 15 capacity, and means for displacing the lubricant from the high pressure cylinder.

Second, to provide a compressor, such as described, with novel means for insuring the priming or refilling of the high pressure 20 cylinder after each discharge of lubricant therefrom.

Third, to provide a compressor, such as described, in which the high pressure cylinder reciprocates relatively to the low pressure 25 cylinder, and in which novel means are provided for preventing leakage along the high pressure cylinder; and

Fourth, to provide a compressor, such as described, that is simple in construction, 30 economical to manufacture and easy to operate.

Other objects of my invention will appear as this description progresses, reference being had to the accompanying drawings, in which 35

Figure 1 is a central, longitudinal section through one embodiment of my invention;

Figure 2 is a transverse section taken on line 2—2 of Figure 1; and

Figure 3 is a view similar to Figure 1, 40 but showing a modified embodiment of my invention.

Throughout the several views similar reference characters are used for referring to similar parts.

45 The embodiment of my invention illustrated in Figures 1 and 2 comprises a barrel, or low pressure cylinder, 5 having a cap 6 at one end that is removably secured thereto through the instrumentality of inclined cam 50 surfaces 7, pressed outwardly from the open end of the barrel, that are adapted to be engaged by lugs 8, pressed inwardly from the flange of the cap.

The opposite end of the barrel 5 is provided with an end piece 9 that tapers out-

wardly so that it terminates in a reduced end portion 10. This reduced end portion is internally threaded to receive the inner exteriorly threaded end of the guide sleeve 11. A high pressure cylinder 12 is reciprocably mounted in the guide sleeve 11 and carries, at its outer end, a nozzle or contact member 13 that has a substantially spherical depression in its outer face adapted to contact with and make sealed connection with 60 fittings such as illustrated in United States Letters Patent No. 1,475,980 that was granted in my name December 4, 1923. A ball check valve 15 is yieldingly held against the outer end of the high pressure cylinder by 65 means of a compression spring 16.

The guide tube 11 is counterbored through a portion of its length to provide an annular space 17 between it and the high pressure cylinder. Packing rings 18 are placed in the 75 outer portion of this annular space and a conical follower 19 rests against the inner packing ring. A compression spring 20, confined between the follower 19 and the inturned flange 21 at the inner end of the 80 guide sleeve, provides means for yieldingly urging the packing toward the outer end of the guide sleeve and thus maintaining the sealing relation to the high pressure cylinder. 85

The means for discharging the lubricant from the high pressure cylinder comprises the plunger 22 that is supported at its inner end by the conical septum or spider 23 that has a plurality of openings 24 formed therein, through which the lubricant can pass. A compression spring 25, confined between the 90 septum 23 and a washer 26 secured to the inner end of the high pressure cylinder, provides means for yieldingly urging the high 95 pressure cylinder to its outermost position.

In order to insure the priming or refilling of the high pressure cylinder after each discharge of lubricant therefrom, I provide the threaded piston rod 27 that is rotatably 100 mounted in the cap or end piece 6 and provided at its outer end with a handle 28, preferably formed of rubber or some other moulded composition. A collar 29, confined between the cap 6 and the handle 28, prevents longitudinal movement of the piston rod 27 in one direction, and a washer 30, resting upon the shoulder 31, formed on the piston rod and confined between this shoulder and the inner face of the cap 6, prevents 105 110

longitudinal movement of the piston rod in the opposite direction.

The piston rod 27 carries a piston P, comprising the face plate 32, the cup leather 33, the follower plate 34 and the intermediate disc 35 of cork, fibre, leather, or other suitable material. These members are provided with registering central openings in which is inserted the sleeve 36, having the flange 37 at one end for engaging the follower plate 34, and the out-turned flange 38 at the opposite end, for engaging the face plate 32. The piston rod 27 and the sleeve 36 are provided with co-acting screwthreads that are 10 preferably lefthanded so that the operator, by holding the handle 28 in his right hand and rotating the barrel of the compressor with his left hand, can easily force the piston toward the high pressure cylinder, thereby 15 placing the lubricant in the barrel or low pressure cylinder under very considerable pressure, although not sufficient to open the check valve 15. Preferably, the elements forming the piston P are held together by 20 means of rivets 39.

In the use of my improved compressor, the cap 6, the piston rod and piston are removed and the barrel is substantially completely filled with lubricant. The cap, the 25 piston and the piston rod are then replaced and the operator, by rotating the barrel relatively to the piston rod, can force the piston inwardly so as to place the lubricant in the barrel under comparatively high pressure. The nozzle or contact piece 13 is then 30 brought into sealing relation with a fitting and the operator exerts a pressure upon the handle 28 in the direction of the fitting, that causes the plunger 22 to enter the high pressure cylinder and discharge the lubricant 35 therefrom into the fitting. When the plunger 22 has completed its stroke, the operator releases the pressure upon the handle 28 and permits the compressor barrel and handle to 40 move away from the fitting, under the tension of the spring 25. The lubricant in the barrel will still be under considerable pressure and will pass into the high pressure cylinder as soon as the end of the plunger 45 has uncovered the inner end of this cylinder. If it is desired to force more lubricant through the fitting, the operator repeats the 50 operation described above as many times as required.

In filling the compressor with lubricant, a certain amount of air will be entrapped therewith, and when the piston P is actuated to place pressure upon the lubricant in the barrel or low pressure cylinder, this air will 55 be compressed and will furnish the expansive force necessary for refilling the high pressure cylinder. In this manner the high pressure cylinder can be primed or refilled several times before it becomes necessary 60 again to turn the barrel relatively to the

handle, or vice versa, to place the lubricant in the low pressure cylinder under pressure. The thread of the piston rod is of comparatively steep pitch, thereby accomplishing two results, first, it prevents the easy development of unduly high pressure in the low pressure cylinder that might otherwise open the valve 15 and permit the loss of lubricant, and second, it enables the operator quickly to 65 move the piston P into pressure contact with the lubricant.

In order to further prevent the development of excessive pressures in the low pressure cylinder, I prefer to make it of large 70 diameter as compared with the diameter of the high pressure cylinder 12, or rather, in comparison to the area of the check valve 15 exposed to the pressure of the lubricant. It will be understood that the tension of the 75 spring 16 will also determine the pressure that can be developed in the low pressure barrel without opening the check valve 15.

It will be noted that there is a space between the inner end of the high pressure cylinder and the inturned flange 21 on the 80 guide sleeve that permits lubricant pressure to be exerted upon the rear of the packing rings 18, so that the pressure of the lubricant itself assists in sealing the joint 85 between the guide sleeve and the high pressure cylinder.

That form of my invention illustrated in Figure 3 is similar to the one just described, except that here the piston rod 27' is 90 threaded in the sleeve 29' that is formed integrally with the cap 6, and with the further exception that the piston P is secured to the inner end of the piston rod 27' which is reduced in diameter, as shown at 27^a, and headed, as shown at 27^b, to hold the 95 elements of the piston in assembled relation on the inner end of the compressor. Here I have shown the piston rod 27' as being provided with a right-handed screw-thread which will function satisfactorily, although it is not as handy to operate as a piston provided with a left-handed screw-thread.

The invention disclosed and claimed herein 100 is a modification of the invention disclosed and broadly claimed in my copending application, Serial No. 649,704, filed July 5, 1923.

While I have described the details of construction of the preferred embodiments of 105 my invention, it is to be clearly understood that my invention is not limited to these details of construction, but is capable of other adaptations and modifications within the scope of the appended claims.

Having thus described my invention, what 110 I claim is:

1. A lubricant compressor comprising a 115 barrel having a removable end piece at one end and an end piece at the other end having a portion of reduced diameter, a guide sleeve 120

secured in said portion of reduced diameter, a cylinder reciprocable in said guide sleeve and terminating in a contact piece, a spring for urging said cylinder outwardly, said guide sleeve having a counter-bore forming an annular space around said cylinder, packing in said annular space, a spring confined in said annular space for urging said packing toward one end of said annular space, a plunger carried by said barrel for displacing the contents of said cylinder, a piston rod rotatably mounted in said removable end piece, and held against longitudinal movement, said piston rod having a left-handed thread of coarse pitch, a piston threaded on said piston rod, and a handle for the outer end of said piston rod.

2. A lubricant compressor comprising a barrel having a removable end piece at one end and an end piece at the other end having a portion of reduced diameter, a guide sleeve secured in said portion of reduced diameter, a cylinder reciprocable in said guide sleeve and terminating in a contact piece, a spring for urging said cylinder outwardly, a plunger carried by said barrel for displacing the contents of said cylinder, a piston rod rotatably mounted in said removable end piece and held against longitudinal movement, said piston rod having a left handed thread of coarse pitch, a piston threaded on said

piston rod, and a handle for the outer end of said piston rod.

3. A lubricant compressor comprising a barrel having a removable end piece at one 35 end and an end piece at the other end having a portion of reduced diameter, a guide sleeve secured in said portion of reduced diameter, a cylinder reciprocable in said guide sleeve and terminating in a contact 40 piece, a spring for urging said cylinder outwardly, a plunger carried by said barrel for displacing the contents of said cylinder, a piston rod rotatably mounted in said removable end piece and held against longitudinal 45 movement, a piston threaded on said piston rod, and a handle for the outer end of said piston rod.

4. A lubricant compressor comprising a barrel having an end piece at each end, a 50 guide sleeve secured to one end piece, a cylinder reciprocable in said guide sleeve and terminating in a contact piece, a plunger carried by said barrel for displacing the contents of said cylinder, a piston rod rotatably mounted in said removable end 55 piece, a piston operated by rotation of said piston rod, and a handle for the outer end of said piston rod.

In witness whereof I hereunto subscribe 60 my name this 17th day of January, 1925.

OSCAR U. ZERK.
